UNITED STATES PATENT OFFICE.

JAMES W. IVORY, OF PHILADELPHIA, PENNSYLVANIA.

TOOTH OR DENTAL CLAMP.

SPECIFICATION forming part of Letters Patent No. 678,182, dated July 9, 1901.

Application filed August 3, 1900. Serial No. 25,825. (No model.)

To all whom it may concern:

Be it known that I, JAMES W. IVORY, a citizen of the United States, residing in the city and county of Philadelphia, State of Pennsylvania, have invented a new and useful Improvement in Tooth or Dental Clamps, which improvement is fully set forth in the following specification and accompanying drawings.

My invention consists of an improvement 10 in a tooth-clamp having a jaw adapted to be pressed against the gum and moved or shifted so as to uncover or expose a marginal cavity of a tooth or for other purposes and then controlling said gum, the novel features being 15 hereinafter described, and pointed out in the claims which follow the specification.

Figure 1 represents a perspective view of a tooth-clamp embodying my invention. Figs. 2 and 3 represent views of opposite faces 20 thereof. Fig. 4 represents a longitudinal section thereof. Fig. 5 represents a longitudinal section of a modification. Fig. 6 represents a face view of the clamp provided with a supplemental jaw. Fig. 7 represents a longitudinal section thereof.

Similar letters of reference indicate corresponding parts in the figures.

Referring to the drawings, A designates an arched frame having a jaw B at the crown 30 thereof.

C designates the shank of said frame, the same having mounted thereon at the outer end thereof the screw D, which is swiveled on the shank E of the opposite jaw F, it being noticed that said shank E has a longitudinally-extending slot G therein to receive the swiveled end of said screw D, whereby said end may have a certain play in said slot.

H designates a post which serves to connect the shanks C and E, forming somewhat of an axis for the jaws B and F, said post having heads on its opposite ends, whereby it is prevented from disconnection, it being noticed that the shank C has a series of connected openings J therein, and the post is formed with the neck K, whereby by manipulating said post so that the neck thereof receives the walls of the opening J the post may be fitted in either of the openings J, while the 45 opposite end of the post is adapted to move in the slot G of the shank E, the swiveled end of the screw also yielding, whereby the ad-

justment of the jaws may be readily accomplished.

It will be noticed that the post H forms a 55 free connection for the shanks of the jaws and is adapted to vary its angle or oscillate as the jaws are shifted in order to effect their adjustment on the tooth, and when the adjustment is accomplished the screw D is properly 60 rotated.

It will be seen that when the jaws are properly located on the labial and palatal or lingual sides of a tooth and the clamp is properly tightened by the screw D the jaw B may 65 be moved or shifted, so that as it bears against the gum it may uncover or expose a marginal cavity which may exist in said tooth and then control the gum in the position it occupies, it being evident that owing to the oscillating 70 nature of the post H and the seating of the swiveled end of the screw in the slot G the jaw B is adapted to have the aforesaid motion imparted to it without disturbing the jaw F in its hold or engagement with the neck of 75 the tooth.

In Fig. 5 the construction of the parts is similar to that hereinbefore described, excepting that the shank E is provided with a series of recesses L, in either of which the 80 point of the screw is freely seated, thus permitting the screw to oscillate in the adjustment of the jaw.

In order to obtain increased holding action of the clamp on a tooth, I employ the supplemental jaw M, which bears against the face of the tooth adjacent to the jaw B and has its shank N formed with a longitudinally-extending slot P, through which pass the post H and the screw D, it being noticed that the 90 back of the jaw M contacts with the base of the frame A, and the shank N, which is deflected from said jaw, bears against the shank E, whereby when the screw D is properly rotated to tighten the clamp on the tooth the 95 jaw M is also firmly pressed against the tooth, providing an additional connection for the clamp with the tooth, while permitting the jaw B to be moved to uncover the marginal cavity without necessarily disturbing said 100 jaw M, at least to any appreciable extent.

Having thus described my invention, what I claim as new, and desire to secure by Letters Patent, is—

1. A tooth-clamp having jaws, carriers on the same, a tightening device for said jaws, and a post which is separate from said tightening device and freely fitted in openings in 5 said carriers and adapted to oscillate in the motions of either jaw.

2. In a tooth-clamp of the order described, a pair of jaws, slotted shanks carrying the same, the slots of one shank being in series, 10 a tightening device on said shanks for closing said jaws and a post which is independent of said device and connected with said shanks and freely occupying the slots therein, said post being also provided with a neck, 15 whereby it may be seated in either of the slots of the respective shank.

3. In a tooth-clamp of the character stated, a pair of jaws, a supplemental jaw interposed

between the same, a tightening device for said jaws and an oscillating post which is 20 mounted on the shanks of said jaws separate from said device.

4. In a tooth-clamp, a pair of jaws and means for tightening the same, in combination with a supplemental jaw which is interposed between the members of the former and adapted to coact with the same in the holding action on a tooth without materially interfering with the motion of the gum shifting jaw and with an oscillating post which is 25 30 mounted on the shanks of said jaws separate from said tightening means.

JAMES W. IVORY.
